UNITED STATES PATENT OFFICE.

RICHARD H. SHADRICK, OF MINNEAPOLIS, MINNESOTA, ASSIGNOR TO ANDREW E. CARLSEN, OF MINNEAPOLIS, MINNESOTA.

SAFETY CUT-OUT FOR GAS MAINS AND THE LIKE.

Application filed February 12, 1927. Serial No. 167,760.

This invention relates to safety cut out devices for gas mains and the like, and the primary object is to provide means of a novel, practical and efficient nature for closing a valve in a lead-in gas main to a building, thereby cutting off the supply of gas to the building in case of fire. The device is so constructed that it will, by a thermally responsive releasing means, be automatically actuated when influenced by the higher temperature of the burning building, and may also be manually actuated, when necessary, from a remote station, which is preferably arranged at the exterior of the building where it is quickly and readily accessible to firemen or others who may not be able to enter the building because of fire or smoke, or because the building may be unoccupied.

The present disclosure is a continuation in part of my co-pending application Ser. No. 60,632, filed October 5, 1925, and renewed December 31, 1926, for valve actuator; and has also some features in common with my co-pending application Ser. No. 159,350, filed January 6, 1927, for thermostatic control.

In the drawing forming a part of the present application, Fig. 1 is a perspective view of a portion of a building or foundation wall, and illustrating the preferred method of installing my improved safety cut out. Fig. 2 is a sectional detail view of the actuator box as seen substantially on the line 2—2 in Fig. 3. Fig. 3 is an elevation of the gas main and the safety valve, the latter being broken away in part, and also showing the actuator box in section about on the line 3—3 in Fig. 2. Fig. 4 is a detail perspective view of a portion of the actuator box, and illustrating the arrangement of parts therewithin. Fig. 5 is a detail section view illustrating the construction of the remote station and one of the pulley elbows used to guide the actuator or pull cable.

Referring to the drawing more particularly and by reference characters A designates the wall of a building or building foundation, through which extends a gas main or supply pipe B. Suitably connected in the main B I provide a valve C, the same being of a common and well known construction in which a valve head 6 is yieldingly pressed toward a seat 7, by a spring 8. The valve head 6 is provided with a stem or pin 9 which projects out through a stuffing box in the neck 10 of the valve. The valve is of

course yieldably closable by the spring 8 but is adapted to be opened and held open by depressing the pin 9.

Rigidly secured to and carried by the valve C is a box 11, the cover 12 of which is hinged, as at 13, and has a lever acting contact with the pin 9, whereby when the cover is closed or in its primary position the pin is depressed, and when the cover is released and moves to its secondary position it allows the pin to project under the action of the spring 8.

Secured within the wall, and preferably to its rear wall, is a strip 14, of what is commonly known as "thermostatic metal" 70 the same comprising two layers of metal having different co-efficients of expansion, whereby it will bend or be distorted under variable thermal conditions. The lower end of this strip 14 is secured, as by screws 15, 75 to the box, and is preferably in direct contact therewith so as to be sensitive to the temperature of the box, which, in turn, is influenced by the surrounding atmosphere. To render the thermal strip more sensitive to 80 the atmospheric temperature, however, it may be desirable to provide the upper and lower ends of the box with perforations, such as 16, thus permitting a circulation of air through the box and in direct contact with 85 the strip. The upper end of the strip 14 is spaced from the wall to which it is attached, so as to allow for freedom of movement, and this spacing may be adjusted by a regulating screw 17 having a lock nut 18. 90

Suitably pivoted, as by a pin 19, within the box 11, is a trigger or lever 20, having a rearwardly extending arm 21, for engagement against the upper end of the strip 14, a forwardly extending hook 22, and a depending lug 23. The door 12 is provided with an angle iron bracket 24, the projecting arm of which has a recess 25 to receive the hook 22 when the door is closed.

Normally, the parts described are in the 100 positions shown in the drawing. When the temperature of the box increases or rises, however, the thermal strip 14 bends or distorts so that its upper end moves toward the rear wall. This releases the lever arm 21, 105 and the door 12, being under the pressure of the spring 8, trips the hook 22 upwardly to release the bracket 24, and thus permits the door to swing open, allowing the valve to close and shut off the gas supply. The lever 110

20 has now assumed the position indicated by dotted lines in Fig. 3.

When the fire is extinguished, or the danger of fire has passed, and it is desired to restore the gas supply, it is only necessary to shut the door 12. This depresses the pin 9, to open the valve, and as the bracket arm strikes the lug 23, it moves it rearwardly, thus reengaging the hook 22, and causing 10 the arm 21 to snap up into position against the upper end of the strip 14, which strip, after cooling off resumes its initial position.

The means for manually closing the valve includes all the elements thus far described, 15 but it does not depend upon temperature conditions to influence the strip 14 for releasing the trigger lever 20.

Secured, as by screws 26, upon an inner side wall of the box 11, is a spring or flexible lever 27, the upper or movable end of 20 which is provided with a right angle extension 28. The rear edge of this extension is cut at an angle with respect to the plane of the strip 14, and contacts with this strip in such a manner that when the upper end of 25 the spring is moved away from the adjacent wall, the angled edge of the extension 28 will exert a cam acting pressure against the thermal strip so as to spring its upper end rearward and thus release the lever arm 21. The movement thus described is effected by a suitable cable 29, which extends out through the opposite side wall of the box and through suitable pipe or conduit 30 to the 35 pull station D. Elbows 31, in such piping, are preferably provided with pulleys 32, for guiding the cable.

The station D comprises a small box 33 having a door 34, which may either have a 40 glass window which may be broken to gain access, or may be provided with a lock 35, which can only be opened by authorized persons such as householders, policemen or firemen. Within the box the end of the cable 29 is provided with a suitable terminal member such as a pull ring 36, which is of course 45 the function of the box to properly house and protect.

It may here be noted that all the mechanism is either substantially enclosed or 50 forms a part of the enclosing structure, thus leaving no parts exposed which can be upset or disturbed either accidentally or by tampering. This is particularly true and of 55 great importance in connection with the box 12, as it contains the most delicate and sensitive parts, and, as it exposes no working parts, it presents little temptation for tampering by persons who might be so inclined 60 and who might easily disturb the proper adjustments, and might possibly render the device inoperative.

It is understood that suitable modifications 65 may be made in the general design and structural details of the invention as

herein shown and described, provided, however, that said modifications come within the spirit and scope of the appended claims.

Having now therefore fully shown and described my invention, what I claim to be new and desire to protect by Letters Patent is:

1. The combination of a yieldingly closable valve having a projecting valve stem, a box carried by the valve and having a door which when closed will depress the valve stem to hold the valve open, means carried within the box for releasably holding the door shut, and thermally controlled means, within the box, for normally maintaining said door holding means in its operative position and adapted to trip said means to release the door, when said thermally controlled means is subjected to a predetermined temperature.

2. The combination of a yieldingly closable valve having a projecting valve stem, a box carried by the valve and having a door which when closed will depress the valve stem to hold the valve open, said door being releasably held closed, thermally responsive means, contained within the box, for releasing the door, said thermally responsive means normally maintaining the valve closed, and manually operated means, adapted to be controlled from a remote point, for releasing the door.

3. The combination including a valve, means tending to close the valve, a lever member for releasably holding the valve open, a latch mechanism for releasably holding the lever member with the valve in an open position, thermally responsive means, adjacent to the latch mechanism, for holding the same in an engagement with the lever member and adapted to release the latch mechanism from the lever member when subjected to an increase in temperature of a determined degree.

4. The combination including a valve, means tending to close the valve, a lever member for releasably holding the valve open, a latch mechanism for releasably holding the lever member with the valve in an open position, thermally responsive means, adjacent to the latch mechanism, for holding the same in engagement with the lever member and adapted to release the latch mechanism from the lever member when subjected to a predetermined temperature, and manual means, operative at a point remote from the valve, for releasing the latch mechanism from the lever member.

5. The combination including a valve, means tending to close the valve, a lever member for releasably holding the valve open, a latch mechanism for releasably holding the lever member with the valve in an open position, thermally responsive means, adjacent to the latch mechanism, for hold-

- ing the same in an engagement with the lever member and adapted to release the latch mechanism from the lever member when subjected to a predetermined temperature, and manual means, operative at a point remote from the valve, for releasing the lever member to permit the valve to close.
6. The combination including a valve, means tending to close the valve, a lever member for releasably holding the valve open, a latch mechanism for releasably holding the lever member with the valve in an open position, thermally responsive means, adjacent to the latch mechanism, for holding the same in an engagement with the lever member and adapted to release the latch mechanism from the lever member when subjected to a predetermined temperature, and manual means, operative at a point remote from the valve, for disengaging the thermally responsive means from the latch member mechanism to thereby release the lever member and permit the valve to close.
- 25 7. The combination of a spring closable valve, a box arranged adjacent to the valve and having a hinged door, which, when closed, will hold the valve open, means within the box for releasably holding the door closed, thermally responsive means, also contained within the box, for normally maintaining said door holding means in its operative position and adapted to trip said means when subjected to a predetermined temperature, and manually operative means for releasing the door, irrespective of temperature conditions.
8. The combination with a valve having a projecting valve stem, of a box rigidly carried by the valve and having a movable portion adapted to hold the valve open, when in its primary position, and to permit the valve to close, when in its secondary position; a retainer for releasably engaging the said movable portion when in its primary position, and manual and thermally responsive means for respectively effecting the disengagement of the retainer from the said movable portion to permit a movement of the latter to its secondary position.
- 50 9. A safety device for a gas main, comprising a valve in said main, means tending to close the valve, a lever acting member adapted to open the valve, thermostatically releasable means for holding the member with the valve in its open position, said means being operative at a degree of temperature which is lower than that which would fuse any of its parts, and a manually operable device controlled from a point remote from the valve, for effecting the release of the member.
- 60 10. A safety cut-off for a gas main, comprising a valve in the main, means tending to close the valve, a lever acting member
- for opening the valve, a latch for releasably engaging the member to hold it with the valve in an open position, a thermally responsive element for releasably engaging the latch to hold it in its operative position, and means for manually disengaging the element from the latch.
11. A safety cut-off for a gas main, comprising a valve in the main, means tending to close the valve, a lever acting member for opening the valve, a latch for releasably engaging the member to hold it with the valve in an open position, a thermally responsive element for releasably engaging the latch to hold it in its operative position, and means for manually disengaging the element from the latch.
- 75 12. The combination of a valve, means tending to close the same, means for releasably holding the valve open including a thermally responsive element which upon being subjected to a predetermined temperature, will bend and thus effect a release of the valve holding means, and manually operative means for mechanically bending the element to effect the release of the valve holding means.
- 90 13. The combination of a valve, means tending to close the same, means for releasably holding the valve open including a thermally responsive element which upon being subjected to a predetermined temperature, will bend and thus effect a release of the valve holding means, and a manually operative cam acting device for bending the element irrespective of temperature conditions.
- 100 14. The combination of a valve, means tending to close the same, means for releasably holding the valve open including a thermally responsive element which upon being subjected to a predetermined temperature, will bend and thus effect a release of the valve holding means, and a spring member associated with the element adapted to be manually operated for bending the same to mechanically release the valve holding means.
- 105 15. The combination including a yieldingly closable valve, a lever acting member for opening the valve, a latch engageable with the member for holding it with the valve in an open position, a thermally responsive element normally maintaining the latch in its member holding position and adapted to release the latch from said position at an abnormally high temperature, and means, operative by a movement of the member to its valve opening position for restoring the latch to its member holding position.
- 120 16. The combination including a yield-

- 4
- ingly closable valve, a lever acting member for opening the valve, a latch engageable with the member for holding it with the valve in an open position, a thermally responsive element normally maintaining the latch in its member holding position and adapted to release the latch from said position at an abnormally high temperature, and means, operative by a movement of the member to its valve opening position for restoring the latch to its member holding position, and means, including said element, for manually effecting the release of the member.
- 15 17. A safety cut out for gas mains comprising, in combination, a normally open valve in the main, manually operative means extending to a point remote from the valve for effecting a closing of the valve, and thermostatically operative means for effecting a closing of the valve, said thermostatically operative means being rendered operative at a degree of temperature which is higher than normal room temperature but lower than that which would fuse any of its parts, said thermostatically operative means including a strip of bi-metal which bends when subjected to variations in temperature.
- 20 18. A safety cut out for gas mains comprising, in combination, a normally open valve in the main, manually operative means
- 5 25 for effecting a closing of the valve, thermostatically operative means for effecting a closing of the valve, said thermostatically operative means being rendered operative at a degree of temperature which is higher than normal room temperature but lower than that which would fuse any of its parts, and means for adjusting the thermostatically operated means whereby it may be caused to operate at any desired degree of temperature within said mentioned range of temperature.
19. A safety cut off for gas mains comprising, in combination, a normally open valve in the main, manually operative means extending to a point remote from the valve for effecting a closing of the valve, and thermostatically operative means for effecting a closing of the valve, said thermostatically operative means being rendered operative at a degree of temperature which is higher than normal room temperature but lower than that which would fuse any of its parts, said thermostatically operative means including a strip of bi-metal which bends when subjected to variations in temperature.
